UNITED STATES PATENT OFFICE.

JOHN M. WITMER, OF LANCASTER, PENNSYLVANIA.

LIXIVIATOR.

1,288,469.

Specification of Letters Patent. Patented Aug. 28, 1917.

Application filed May 5, 1916. Serial No. 95,731.

To all whom it may concern:

Be it known that I, JOHN M. WITMER, a citizen of the United States, residing at Lancaster, in the county of Lancaster and State of Pennsylvania, have invented certain new and useful Improvements in Lixiviators, of which the following is a specification, reference being had therein to the accompanying drawing.

10 This invention relates to an apparatus for recovering gold and silver by the cyanid method from ore, and the device not only combines the features of a lixiviator, but pulverizes or regrinds the ore while it is 15 being treated by the cyanid solution under ideal conditions.

While I am fully aware that there have been several machines devised for this purpose, none of them have been of practical 20 commercial value, the greatest trouble being that they become clogged with the wet ore, which, when pulverized to the fine mesh required, becomes pasty and settles like cement.

25 The object of the present invention is to provide an apparatus or machine for this purpose, that shall be self-cleaning and which will not become clogged, even should it be stopped.

30 Another object being to provide means whereby the ore during its passage through the machine, becomes constantly reground or pulverized, while at the same time being constantly exposed to the action of the cyanid under the most favorable conditions.

Another object being to so construct a 35 machine of this kind that every grain of finely pulverized ore shall be treated alike, and the ore and solution shall at all times be evenly distributed over the machine and prevented from settling in any part.

40 A further object is to provide a machine of rough, substantial construction, easily transported and renewed, requiring a small 45 amount of water and cyanid and no skilled labor.

With these and other objects in view, my 50 invention consists in certain construction and combination of parts as will hereinafter be fully described and claimed in the specification, and illustrated in the accompanying drawings, which form a part of this application, and in which like figures of reference refer to corresponding parts in 55 all of the views; but it is fully understood

that while I have here described my device as shown, that I do not confine myself to the exact design, as slight changes may be made in the construction and arrangement of the several parts without departing from 60 the spirit of the invention.

In the drawings:—

Figure 1, is a side elevation of the apparatus.

Fig. 2, is an enlarged side elevation, partly 65 in section, of one of the triangles and operating means.

Fig. 3, is a top plan view of the first trough.

Fig. 4, is a detail cross sectional view of 70 the rocking cradle.

Fig. 5, is a detail sectional view of the air valve.

Fig. 6, is a partial sectional view of Fig. 3.

Fig. 7, is a top plan view of one of the 75 troughs.

Fig. 8, is a bottom plan view of the same.

Fig. 9, is a cross sectional view of Fig. 7, taken on the line X—X.

Fig. 10, is a cross sectional view of Fig. 7, 80 taken on the line Y—Y.

Fig. 11, is an end view of Fig. 7.

Referring to the drawings, the apparatus comprises a series of troughs mounted on a supporting frame 1, which is inclined at a 85 suitable angle, the number of troughs required to comprise a simple machine depending entirely on the class of ore which is to be treated, as some ores are refractory and require a longer treatment than do 90 others.

As the troughs, with the exception of the first or pulverizing trough, are all constructed alike, and are arranged in series, each discharging into the next or lower one, it 95 will be sufficient to explain in detail, the construction of the trough shown in Figs. 2, 7, 8, 9, 10, and 11, which is constructed as follows:—

The upper end is formed with a receiving 100 basin 2, having an inclined portion 3, leading to the main bottom 4, of the trough, which is formed with a drop 7, dividing it into the parts 4, and 5, the part 5, being provided with the discharging lip 6, for conveying the material into the basin 2, of the adjacent trough.

The receiving basin 2, is provided with a grooved bottom 8, which may be detachable and thus removable, or be integral with said 110

basin. The bottom of the trough, or parts 4, and 5, are each provided with a false bottom or plates, 9, and 10, which are preferably a hard material, and readily removable, after 5 becoming worn.

Under the bottom 4, is provided a heating chamber 11, which may be supplied with steam by the pipes 12, and 13, from a steam supply pipe 14, as shown in Fig. 2, or the 10 part 4, of the trough bottom may be heated in a direct manner by a gas burner; the control of the heat being effected by the valves 15, 16, and 17. The valves 15, and 16, being opened, and the valve 17, closed, when it is desired to heat the plate, and the valve 17, opened, and valves 15, and 16, closed, when 15 it is desired that the steam pass without heating the plate.

A heating dome or deflector 18, is also 20 provided on the bottom of the part 5, which may be heated by a gas flame or electricity if desired.

In the basin 2, is mounted on the trunnions 19, in the bearings 20, a rocking cradle 25 21, formed with three ribs or leaves 22, each having teeth 23, adapted to enter the grooves 24, in the plate or curved bottom 8. Said cradle 21, having ends 25, and a dividing wall 26, midway its ends, and operated by a combined lever and air valve 27, attached thereto, and pivoted at 28, to an arm 29, secured to the combined operating rod and air tube 30, which is reciprocated by a rod 31, driven by a crank 32, mounted 30 on a shaft 33, which is rotated by a pulley 34, driven by the belt 35.

Referring to the detail construction of the arms 27, and 29, shown in Figs. 4, and 5, the arm 27, is provided with two air ducts 40 36, the lower ends of which communicate with the part of the chamber formed in the cradle 21; while the upper ends of said air ducts 36, communicate with the inner surface of the joint 37; the arm 29, being provided with an air duct 38, the upper end 45 of which communicates with the air supply pipe 30, and the lower end of which communicates with the inner surface of the joint 37.

50 It will thus be seen that when the arms 27, and 29, assume a straight line position, the opening 39, of the duct 38, will be between the openings 40, and 41, of the ducts 36, and no air can pass through said ducts, 55 but as the cradle 21, is rocked, the opening 39, will register for a brief time with, first, the opening 40, and then with the opening 41, thus admitting compressed air, first to one chamber of the cradle, and then to the 60 other chamber, the air always being admitted to the chamber which is down, and closed by its walls 21, and 22, being submerged in the ore and solution.

The parts 4, and 5, of the trough are each 65 supplied with a friction plate 42, which is

reciprocated upon the bottom plates 9, and 10, for rubbing, scouring and pulverizing the ore. Said plates 42, are connected together by the rods 43, which are pivoted together at 45, and are operated by the rod 70 46, which is pivoted to the arm 29; or if desired, the rods 43, may be secured to a rod 47, which is reciprocated at a higher speed than the pipe 30, by a rod 48, operated by a crank 49, secured on a shaft 50, 75 and driven by a pulley 51, and belt 52; and if this is used, the rod 46, is removed. The rod 47, is provided with a suitable weight 53, for supplying pressure to the friction plates 42. The first, or pulverizing trough 80 54, is formed with a receiving end 55, into which the ore and solution are conveyed by a conveyer 56, and spout 57, and the lower end of said trough 54, discharges into the basin 2, of the upper trough. 85

The trough 54, is provided at its receiving end with transverse corrugations 58, (Fig. 6); while above said trough is a reciprocating rod 59, operated by an arm 60, pivoted to a crank 61, and a shaft 62, driven by a 90 pulley 63, and belt 64. Secured to said rod 59, are several rubbing and pulverizing blocks 65, having plates 66, secured to their lower surfaces to form a rubbing contact with the surface of the trough 54. Said 95 plates 66, being reversible, and formed with surfaces as shown in Fig. 3, the first being very coarse, and the last nearly smooth, and all being provided with counter-sunk holes 67, to retain air and solution. 100

There is also attached to the rod 59, a member 68, having a corrugated bottom and adapted to rock in the corrugations 58, for the purpose of first grinding the ore and solution before it passes under the plates 65. 105

Referring to Fig. 7, it will be seen that each trough may be divided longitudinally by the low walls, which are only as high as the thickness of the plates 42, into three compartments, within each of which is 110 mounted a series of plates 42, and cradles 21, set in different positions, so that the ore and solution cannot run to any part of the trough and become settled, but will be constantly moved all over the trough. 115

In the operation of the device:—

The ore having been ground to, say eighty or one hundred mesh, is mixed with the proper cyanid solution in the mixer, and conveyer 56, and enters the pulverizing 120 trough 54, where it is finely pulverized by the blocks 65, while being exposed to free air and air confined in the holes 67. From here it enters the basin of the first trough, and is further pulverized, agitated, and 125 treated by the compressed air, while free air is admitted at each end of the cradle, and from here it is thrown out on the part 3, and exposed to the atmosphere, and descended to the plate 9, which may be heated 130

or not, as desired; here it is further rubbed and pulverized under partly confined and free air conditions, when it descends to the plate 10, receiving free air during its descent, and is again pulverized by the second plate 42, upon the cool surface 10, and then drops through the cool free air into the basin of the next trough, where the same process is repeated, and so on over every 10 trough until the last, when it is delivered to a filter and the usual zinc receiving boxes, and the solution is returned to the supply tank.

Having thus described my invention what 15 I claim as new, and desire to secure by Letters Patent is:—

1. In a lixiviator of the class described, in combination with a series of inclined troughs or pans, each mounted upon a lower level 20 than the preceding one, and each formed with a receiving basin and a delivering lip, of a grinding and mixing cradle mounted in said basin and adapted to be oscillated therein, the bottom of said pans provided 25 with means for heating the same, a combined scouring, rubbing and pulverizing means mounted in said pans, and means for supplying compressed air to said cradle in an 30 intermittent manner.

2. In a lixiviator of the class described, in combination with a series of troughs or pans mounted in an inclined manner, each upon a lower level than the preceding one, and each provided with a receiving basin and a discharging lip, said receiving basin formed 35 with a curved corrugated bottom, a cradle mounted in said basin, teeth formed on the edges of said cradle adapted to fit the corrugations in the bottom of the basin, means 40 for oscillating said cradle within said basin, and means for applying compressed air

within said cradle in an intermittent manner.

3. In a lixiviator of the class described, in combination with a series of troughs or pans 45 mounted each upon a lower level than the preceding one, and each provided with a receiving basin and delivering lip, the bottom of said pan being divided into two surfaces on different levels, and both on a lower level 50 than the delivery edge of the basin, plates secured upon said surfaces, rubbing plates formed with grooved surfaces and orifices therethrough, mounted upon said plates, and means for reciprocating them thereon. 55

4. In a lixiviator of the class described, in combination with a series of troughs or pans, each upon a lower level than the preceding one, and each provided with a receiving basin and delivering lip, the surface of said 60 pan provided with grinding and pulverizing means, and the lower surfaces of said pans provided with means for heating the same.

5. In a lixiviator machine of the class described, a series of pans mounted in an inclined manner, each delivering into the succeeding one, a rubbing or pulverizing trough mounted before the first pan and delivering therein, pulverizing and mixing means mounted in said pulverizing trough, means 65 for delivering ore and solution into said pulverizing trough, means for agitating, aerating and mixing the ore and solution in the pans, means for heating the ore and solution 70 in said pans, means for regrinding and 75 scouring the ore and solution in said pans.

In testimony whereof I affix my signature in presence of two witnesses.

JOHN M. WITMER.
